(57) **CLAIM**

The ornamental design for a display device, as shown and described.

DESCRIPTION

FIG. 1 is a perspective view of the display device of the present design;

FIG. 2 is a front view of the display device shown in FIG. 1;

FIG. 3 is a back view of the display device shown in FIG. 1;

FIG. 4 is a front view of the display device shown in FIG. 1 with a watch;

FIG. 5 is a side view of the display device shown in FIG. 1 with a watch;

FIG. 6 is a perspective view of the display device shown in FIG. 1 with a watch;

FIG. 7 is front view of the display device shown in FIG. 1 with a watch;

FIG. 8 is a side view of the display device shown in FIG. 1 with a watch;

FIG. 9 is a perspective view of the display device shown in FIG. 1 with a watch;

FIG. 10 is a front view of the display device shown in FIG. 1 with a watch;

FIG. 11 is a side view of the display device shown in FIG. 1 with a watch;

FIG. 12 is a perspective view of the display device shown in FIG. 1 with a watch;

FIG. 13 a front view of a second embodiment of a display device with a watch;

FIG. 14 is a side view of the display device shown in FIG. 13 with a watch;

FIG. 15 is a perspective view of the display device shown in FIG. 13 with a watch;

FIG. 16 a front view of the display device shown in FIG. 13 with a watch;

FIG. 17 is a side view of the display device shown in FIG. 13 with a watch

FIG. 18 is a back view of the display device shown in FIG. 13 with a watch; and,

FIG. 19 is a perspective view of the display device shown in FIG. 13 with a watch.

The broken lines in the drawings are used to illustrate unclaimed environment and form no part of the claimed design.

1 Claim, 6 Drawing Sheets
